UNITED STATES PATENT OFFICE.

CHARLES L. LILLEBERG, OF CHICAGO, ILLINOIS.

SHEET-TRIMMING MACHINE.

1,120,394.

Specification of Letters Patent.

Patented Dec. 8, 1914.

Application filed March 24, 1913. Serial No. 756,619.

To all whom it may concern:

Be it known that I, CHARLES L. LILLEBERG, citizen of the United States, residing at Chicago, in the county of Cook and State of Illinois, have invented a certain new and useful Improvement in Sheet-Trimming Machines, of which the following is a full, clear, concise, and exact description, reference being had to the accompanying drawings, forming a part of this specification.

My invention relates to machines for trimming the longitudinal edge portions of thin flexible sheet material such as paper and is of particular service in connection with the preparation of paper that is to be operated upon by perforating mechanism employed in making perforated sheet music, though the invention is not to be limited to this service. I have found that as the paper is fed to the perforating machine it follows a slightly sinuous path, it being impossible to cause it to travel in an exactly straight line. The paper, as it is fed to the perforating machine, thus shifts laterally in its direction of travel due to the uneven tension of the paper itself, it being impossible to produce the paper of uniform tension. That is, the paper is more taut in parts than it is in other parts, a feature that obviously will cause the paper to feed unevenly.

In practising my invention I employ two cutter rollers between which the paper is fed to the perforating machine, in combination with means for properly directing the paper with respect to these rollers so that the rollers may operate thereupon to trim the longitudinal edges of the sheet passing to the perforating machine, the trimmed sheet passing the perforating machine moving in a substantially straight line or single vertical plane of travel, whereby the various rows of perforations are in straight lines rather than in sinuous lines as was hitherto the case. Thus I am enabled to produce sheet music which will properly track upon the tracker boards of the musical instruments in connection with which it is used and I am also enabled to produce sheet music which will wind and unwind evenly, an advantage that is of especial utility in connection with the rewinding of the sheet music which is done at a high rate of speed compared with the unwinding of the sheet. As the paper passes from one spool to the other it will move in a substantially single plane so that the edges

of the paper will not become frayed, hemmed or cracked.

I will explain my invention more fully by reference to the accompanying drawing 60 showing the preferred embodiment thereof and in which—

Figure 1 is a view in elevation, partially in section, of a machine constructed in accordance with the invention; Fig. 2 is a 65 sectional elevation of part of the structure illustrated in Fig. 1; Fig. 3 is a plan view of part of the structure illustrated in Fig. 1; and Fig. 4 is a view on a smaller scale of one of the structural parts shown in Fig. 1. 70

Like parts are indicated by similar characters of reference throughout the different figures.

The paper to be trimmed and perforated is disposed upon a supply spool 1 from 75 which it is fed or drawn between cutter rolls 2 and 3, the paper after being trimmed passing underneath and in contact with a grooved cylindrical cutter roller 4 forming a part of the preferred form of cutting machine which I employ but to which cutting machine the invention is not to be restricted, such a cutting machine being illustrated in Patent 854,822, granted to A. L. Hart, May 28, 1907. The mechanism for drawing the 85 paper from between the cutter rollers is located at the right of the cutting cylinder 4 and is so well known as not to require illustration. A suitable braking appliance is applied to the spool 1 so that the paper as 90 it is drawn between the cutter rolls 2, 3 is placed under sufficient tension properly to be subject to the action of the cutter rolls, such a braking device being illustrated in Fig. 4. In Fig. 4 one end wall of the spool 95 1 is grooved to receive a cord 5 anchored at its right hand end to the frame of the machine and at its left hand end carrying a number of removable weights 6, these weights being reduced in number as the 100 paper is withdrawn from the spool 1 so as to render the tension upon the paper being fed between the cutter rolls sufficiently substantially uniform. The axes of the spool 1, cutter roller 3, and cylinder 4 are so relatively located that a bight is formed by the cutter roller 3 in the paper which is being trimmed, the cutter roller 3 being within the bight while the cutter roller 2 is without the bight. This bight in the paper that is 110 being tautly drawn from between the rollers 2, 3 serves so to present the paper to the

2 cutting portions of the rollers as most effectively to trim the longitudinal edges of the passing sheet. The cutter roller located within the bight is a male cutter roller and the cutter roller without the bight is a female cutter roller, this latter cutter roller having flanges 7 spaced apart a distance to receive the roller 3, the edges of the roller 3 and the adjacent edges of the flanges 7 constituting cutting edges which coöperate to trim the longitudinal margins of the paper as indicated most clearly in Fig. 3, the marginal strips undergoing removal being indicated at 8. The paper being passed between 15 the cutter rolls serves to turn both cutter rollers which are preferably unprovided with any other driving means, the mountings for both ends of each cutter roller being similar to that shown in Fig. 2. The roller 20 2 preferably operates by gravity to perform its function. The lower roller has a fixed axis of rotation which is determined by the pivot screws 9. The screws 9 are adjustable longitudinally of the roller 3 so as to define the location of the lines along which the trimming of the paper is to take place. The adjustment of the roller 3 is automatically accompanied by a corresponding adjustment of the roller 2 owing to the interposition of 25 30 the roller 3 between the flanges 7 of the roller 2. When the desired adjustment has been secured it is maintained by the clamping nuts 10. It is obvious that the adjustment of the rollers 2 and 3 may be effected 35 while the paper is traveling between the same so that the paper may be fed to the perforating machine in proper position with respect to the cutting mechanism thereof without the necessity of adjusting the spool 40 1. In the construction of the rollers 2 and 3 the cutting ends of the roller 3 desirably form separable parts 3¹ that are in screw connection with the balance of the roller 3, lock nuts 3² serving to hold the roller sections 3¹ in proper position with respect to the balance of the roller 3. The flanges 7 are likewise separately formed and are in screw connection with the balance of the rollers 2, these flanges 7 abutting against the 45 50 interposed section of the roller 2 where they are in fixed position. The space between the cutting flanges 7 determines the width of the paper and the roller ends 3¹ are positioned so as to be in nice cutting relation with the flanges 7 to cut the paper exactly the 55 60 width of the space between the flanges 7. After the paper has been perforated by the perforating machine it is wound upon spools, the faces of the paper rolls being very smooth as a consequence of the employment of the device of my invention. Any suitable means may be employed for directing the strips 8 away from the trimmed portion of the sheet, such as the directing flingers 11 shown in Figs. 1 and 3.

While I have herein shown and particularly described the preferred embodiment of my invention I do not wish to be limited to the precise details of construction shown as changes may readily be made without departing from the spirit of my invention, but

Having thus described my invention I claim as new and desire to secure by Letters Patent the following:—

1. A machine for trimming the longitudinal edges of sheet material including freely mounted rollers between which the sheet to be cut is passed and which engage said sheet to be driven thereby, one of said rollers being so located with respect to the passing sheet as to form a bight therein, the other roller engaging the sheet at and without the bight, the bight forming roller having a cutter portion at each end of a diameter similar to that of the balance of the bight forming roller and underlying the other roller, while the roller without the bight carries cutters coöperating with the aforesaid cutter portions of larger diameter than this outer roller, the bight forming roller and its cutter portions being together interposed between the cutters carried by the companion roller, two of the coöperating cutting elements being relatively adjustable longitudinally of the rollers to determine the width of the sheet to be cut.

2. A machine for trimming the longitudinal edges of sheet material including freely mounted rollers between which the sheet to be cut is passed and which engage said sheet to be driven thereby, one of said rollers being so located with respect to the passing sheet as to form a bight therein, the other roller engaging the sheet at and without the bight, one of these rollers having a cutter portion at each end of a diameter similar to that of the balance of this roller, while the other roller carries cutters coöperating with the aforesaid cutter portions of larger diameter than this other roller, the first roller and its cutter portions being together interposed between the cutters carried by the companion roller, two of the coöperating cutting elements being relatively adjustable longitudinally of the rollers to determine the width of the sheet to be cut.

3. A machine for trimming the longitudinal edges of sheet material including freely mounted rollers between which the sheet to be cut is passed and which engage said sheet to be driven thereby, one of said rollers being so located with respect to the passing sheet as to form a bight therein, the other roller engaging the sheet at and without the bight, the bight forming roller having a cutter portion at each end of a diameter similar to that of the balance of the bight forming roller and underlying the other roller, while the roller without the bight

carries cutters coöperating with the aforesaid cutter portions of larger diameter than this outer roller, the bight forming roller and its cutter portion being together interposed between the cutters carried by the companion roller.

4. A machine for trimming the longitudinal edges of sheet material including freely mounted rollers between which the sheet to be cut is passed and which engage said sheet to be driven thereby, one of said rollers being so located with respect to the passing sheet as to form a bight therein, the other roller engaging the sheet at and without the bight, one of these rollers having a cutter

portion at each end of a diameter similar to that of the balance of this roller, while the other roller carries cutters coöperating with the aforesaid cutter portions of larger diameter than this other roller, the first roller and its cutter portions being together interposed between the cutters carried by the companion roller.

In witness whereof, I hereunto subscribe my name this twenty fourth day of January 25 A. D., 1913.

CHARLES L. LILLEBERG.
